UNITED STATES PATENT OFFICE.

JOHN F. KEITHMAN, OF CHICAGO, ILLINOIS, ASSIGNOR OF ONE-FOURTH TO WILLIAM F. MANAHAN, OF YORKTON, CANADA.

ADJUSTING TABLE.

Application filed June 23, 1923. Serial No. 647,289.

To all whom it may concern:

Be it known that I, JOHN F. KEITHMAN, a subject of the King of Great Britain, residing at Chicago, in the county of Cook and State of Illinois, have invented new and useful Improvements in Adjusting Tables, of which the following is a specification.

This invention relates to adjusting tables, and more particularly to adjusting tables of the type such as used by chiropractors, and an object of the invention is to provide an adjusting table which may be collapsed into a relatively small compact structure to facilitate its transportation or carrying about by the physician, in a suitable carrying case.

Another object of this invention is to provide a chiropractic adjusting table which comprises end sections each including a plurality of adjustably connected legs which are connected in such manner that they move synchronously towards each other when collapsed, or away from each other, during opening or movement into operative positions, each of the legs moving an equal distance from the other or from the central collapsed position, and also to provide diagonal braces pivotally connected to each other and, at their upper ends to the supporting legs, certain of the braces being yieldably connected at their lower ends to the legs to permit the synchronous movement during collapsing or spreading.

A further object of the invention is to provide a table as specified in which the central portion of the table is adjustably supported for limited pivotal movement to permit its adjustment to properly fit the abdomen of the patient and also to provide means for yieldably supporting the central portion of the table in adjusted positions.

Another object of the invention is to provide a novel construction for connecting the canvas or fabric top of the table to the side rails thereof and also to provide means for stretching the fabric table top to permit the desired tautness thereof.

A further object is to provide simple and efficient means for securing together and bracing parts of the table structure.

Other objects of the invention will appear in the following detailed description taken in connection with the accompanying drawings wherein:

Fig. 1 is a side elevation of the improved chiropractic adjusting table.

Fig. 2 is a top plan of the table.

Fig. 3 is a top plan of the table frame having the top removed.

Fig. 4 is a detail view showing the supporting leg structures collapsed. 60

Fig. 5 is a detail sectional view taken on the line 5—5 of Fig. 1.

Fig. 6 is a detail section on the line 6—6 of Fig. 3.

Fig. 7 is a detail section on the line 7—7 of 65 Fig. 2 illustrating the manner of connecting the top to the side rails of the table.

Fig. 8 is a detail section on the line 8—8 of Fig. 1.

Fig. 9 is a detail section on the line 9—9 70 of Fig. 1.

Referring more particularly to the drawings, the improved chiropractic adjusting table comprises the leg structures 1, two of which are provided and which are hollow 75 in construction, each leg structure being adapted to support the ends of the table.

Each of the leg structures 1 comprises four legs 2 which are preferably of tubular construction and are connected by diagonal 80 braces 3. Each of the diagonal braces 3 comprises a plurality, preferably three relatively thin metal strips 4 which are held in spaced relation at their ends by spacing collars 5 and are held in spaced relation intermediate their ends by the metal strips of the oppositely extending brace. The braces are pivotally connected intermediate their ends by suitable pins or rivets 6. The lower ends of the braces 3 are pivotally connected 90 to collars 8 which are slidably upon the legs 2. Two of the collars 8 are slidably mounted on each leg 2, and the braces at one side of the leg structure are connected to one of the collars while the braces which extend at 95 right angles to the first mentioned braces are connected to the other collar, as clearly shown in Fig. 1 of the drawings. The collars 8 are yieldably connected so as to permit limited relative movement thereof by means 100 of pins 9 which extend through slots 10 formed in the legs 2 and by coiled springs 11 which are connected to the pins 9 and are positioned within the tubular legs 2, as clearly shown in Fig. 8 of the drawings. 105

The legs 2 have pins 12 on their upper ends which extend into the top side rails 13 of the table structure. The top side rails 13 are preferably tubular and they are braced and connected laterally by adjustable 110

brace structures 14 and 15. The adjustable brace structures 14 and 15 comprises bolts 16 the inner ends of which are connected by turn buckles 17. Heads 18 are mounted on the ends of the rods 16, the heads 18 are substantially triangular shaped and have pins 19 formed thereon one of which engages in a suitable opening in the rail 13, while the other engages in a suitable opening in the legs 2, as clearly shown in Fig. 6 of the drawings. The brace structures 15 have their heads 18 positioned diagonally as shown in Fig. 1 of the drawings so that the pins 19 thereof will serve the dual function of connecting the heads 18 to the legs 2 and rails 13 and also serve as pivot pins for the central pivoted rail extensions 20 which form the middle or central portion of the adjusting table. The pivoted rail extensions 20 are connected transversely of the table by adjustable brace structures 21 which embody turn buckles 22. Depending levers 23 are connected one to each of the pivoted rail extensions 20 and they have their lower ends connected by chains 24, which chains are detachably connected to each pair of levers at the sides of the table. The levers 23 are also connected to the pivoted rail extensions by chains or flexible members 25 while they have springs 26 adjustably connected thereto below the chains 24. By varying the connections of the springs 26 with the respective levers of the pairs, a pressure on and the positions of the rail extensions 20 may be varied to permit adjustment to properly fit the patient. The upward movement of the pivoted rail extensions 20 is limited by chains or flexible members 26' which are connected to the pivoted extensions 20 and to the bracing bars 27. The bracing bars 27 are preferably of tubular construction and have pins 28 carried at their ends which extend into the inner legs 2 of each leg structure 1. Spring fasteners or clips 29 are pivotally carried at each end of the brace bars 27 and they are urged by means of compression springs 30 into suitable openings 31 in the legs 2 for detachably connecting the bars 27 to the leg structures 1 and for connecting the leg structures in table formation.

The table top 35 is preferably formed of canvas, pliable leather or any suitable material and it has strips 36 attached to its under surface and extending longitudinally there along. The strips 36 are connected to the fabric top 35 preferably by fabric loops 36'. Arcuate rail gripping members 37 engage over the rails 13 and 20, at spaced points, engaging in the grooves or notches 39 formed in the upper surfaces of the rails so as to permit the table top to lie perfectly smooth and to eliminate

rough places along the edges of the table. The strips 36 and the pivotal connection between these strips and the members 37 permit adjustment of the rails to stretch the top 35 taut. 65

The table top 35 is stretched and held taut upon the rails by adjustment of the brace structures 14, 15 and 21. It is desirable to have the material of which the top 35 is formed hang downwardly over the outer sides of the rails and rail extensions as shown at 40 in Fig. 7 of the drawings. 70

In Fig. 2 of the drawings pneumatic pillows or cushions 42 of any approved construction are shown. The table top 35 is provided with a longitudinal slot 44 which is positioned between the longitudinally extending pneumatic pillows or cushions 42 and to permit uniform and even stretching of the top 35, at this point, rods or bars 45 are attached to the under surface of the top 35 along each side of the slot 44. The rods 45 are connected by means of flexible chains or analogous members 46. 80

From the foregoing description taken in connection with the accompanying drawings it will be apparent that the improved chiropractic table may be quickly and easily taken apart, by disconnecting the brace structures 14, 15 and 21, and disconnecting the rails 13 and rail extensions 20 from the legs after which the leg structures may be collapsed into the position as shown in Fig. 4 of the drawings. The brace bars 27 may also be quickly and easily disconnected allowing the various rail portions to be folded together and the entire table may be collapsed into a comparatively small space so as to permit it to be carried about by the physician. 90

It is, of course, to be understood that the invention may be constructed in other manners and the parts associated in different relations and, therefore, I do not desire to be limited in any manner except as set forth in the claim hereunto appended. 100

Having thus described my invention what I claim is:

A table of the class described including supporting legs, centrally disposed pins at the upper ends of the legs, top rails having openings to receive the pins, adjustable brace rods, removable head members upon the outer ends of said rods, spaced lugs carried by said head members and said legs and top rails having openings therein to receive the lugs whereby to retain the legs and top rails against movement with respect to each other. 115

In testimony whereof I affix my signature.

JOHN F. KEITHMAN.
